UNITED STATES PATENT OFFICE.

JAMES A. GARLAND, JR., OF HAMILTON, MASSACHUSETTS.

TABULATING ATTACHMENT FOR TYPE-WRITERS.

SPECIFICATION forming part of Letters Patent No. 691,130, dated January 14, 1902.

Application filed September 8, 1900. Serial No. 29,417. (No model.)

To all whom it may concern:

Be it known that I, JAMES A. GARLAND, Jr., a citizen of the United States, residing at Hamilton, in the county of Essex and State of Massachusetts, have invented a new and useful Improvement in Tabulating Attachments for Type-Writers, of which the following is a specification.

The object of this invention is to provide an effective and readily-applied tabulating device for type-writing machines of the traveling-paper-carriage class, of which the Remington machine is a well-known example.

Tabulating attachments are used to assist the operator in writing columns of figures, when unless some mechanical assistant is provided it becomes necessary to stop the paper-carriage manually at suitable points, so that in writing a column of figures the decimal-points shall appear in true vertical column. In so doing the operator is obliged to verify visually the location of the paper-carriage before writing each figure in the column, and although the mechanical tabulating devices heretofore provided assist in this operation to the extent of providing a fixed intermediate stop which arrests the paper-carriage at a point short of its normal limit of travel the operator is still obliged to make occasional visual verification when the denominations of figures in the column change from tens to hundreds and thousands, &c.

My improved tabulating attachment provides means whereby correct tabulation of a column of figures may be made without visual reference to the paper in the machine and whereby the machine is left entirely free to do all its ordinary work without removal or adjustment of the tabulating attachment. It also contains a device for relieving the machine of the shocks which are occasioned when, as in some tabulating attachments, the paper-carriage is released from its detent and allowed to advance without hindrance until it brings up against a stop on the tabulating attachment.

In the drawings hereto annexed I show an embodiment of my invention attached to a Remington No. 6 type-writing machine. Only those portions of the machine with which my invention is immediately concerned are shown in the drawings, as the machine as a whole is

too well known to require illustrative or detailed description. Obviously, however, my invention is adapted to be applied to any type-writing machine which employs a paper-carriage which advances as the written line develops. All the machines of this class are provided with a step-by-step feed mechanism, which gives to the paper-carriage its normal automatic movement of advance, and are further provided with means whereby the normal connection of the paper-carriage with its intermittent feed mechanism may be broken and the carriage moved continuously in the direction of its normal advance. This abnormal movement is usually caused or assisted by the spring or equivalent source of power, which exerts a constant effort to pull the paper-carriage forward and is restrained normally by the step-by-step feed mechanism, which permits the carriage-draft to act only for short spaces at intervals.

In the drawings, Figure 1 represents a front elevation of my tabulating attachment and portions of the machine-frame and paper-carriage; Fig. 2, a side elevation of my tabulating attachment with the machine-frame and paper-carriage partially shown; Fig. 3, a rear elevation of the tabulating attachment and a portion of the paper-carriage rack-bar; Fig. 4, a plan view of the tabulating attachment with portions of the paper-carriage broken away, and Fig. 5 shows in perspective the yielding stop employed in connection with the stop-rack shown in the other figures.

The frame A of the Remington No. 6 type-writing machine provides by its regular construction convenient means for securing my tabulating attachment to the machine. The tabulating attachment is mounted upon a plate E, which is perforated to receive the screw b, Figs. 2 and 4, which secures the plate to the machine-frame A, and is also perforated or recessed, as at a, so as to slip over a stud or boss on the machine-frame. A stop-rack d is fitted to slide in a guide E⁷ in the raised portion E⁸, which is integral with or secured to the plate E. This raised portion is cut away at one end at its rear side, as shown in Fig. 4, so that the gear-wheel e² can mesh with the teeth in the rack d. The gear-wheel e² is rotatively mounted upon the plate E and is actuated at the will of the operator by the

toothed wheel e' , which is mounted upon the stud e^6 and secured to the knurled disk e . The sliding rack d lies parallel with the axis of the paper-carriage just in front of the letter-space feed-rack r , Fig. 4. A stop F , (shown in detail in Fig. 5,) provided with forked legs $f^7 f^8$, is adapted to be placed upon the stop-rack d , said legs straddling the central upper portion d^3 of the stop-bar d , the 10 prongs of the legs extending into the spaces d^4 between the teeth of the stop-rack. The stop F is shown in the drawings as specially designed to afford a cushioned contact for the paper-carriage; but for many purposes a 15 simple clip adapted to rest between the teeth of the stop-rack d will serve equally well. The stop F , as herein shown, consists of a dash-pot, in which slides the piston f^3 , attached to the stem or piston-rod f^2 , whose 20 outer end is laterally bent at f' and terminates in a stop-finger f . The piston f^3 should be prevented from turning by the use of a feather-and-groove device or some equivalent means, so that the position of the finger f may 25 remain constant with reference to the path of travel of the paper-carriage. If desired, vents f^9 are provided in the dash-pot cylinder. A light spring f^5 , Fig. 3, serves to return the piston f^3 to its outer position when 30 released from the pressure of the paper-carriage.

A stop or detent R' is secured to the letter-space feed-rack r by a screw r^4 and hook r^2 . This detent is curved at its lower left-hand 35 end, as viewed in Fig. 1, terminating in a detent-finger r^3 . (Shown in Figs. 2 and 4.)

The letter-space feed-rack r cooperates with the toothed wheel, (not shown,) which is connected with the step-by-step feed movement of the machine, so that when the paper-carriage is in position for writing the normal step-by-step feed is communicated to the paper-carriage by means of the feeding mechanism, toothed wheel, and letter-space feed-rack r . When, however, it is desired to move the paper-carriage in the direction of its normal step-by-step movement without employing the step-by-step feed, the usual release-lever L comes into play. The operator depresses the tread l and raises the opposite end l^3 of the lever L , lifts the letter-space feed-rack out of mesh with its toothed wheel, and thus leaves the carriage free to move under the stress of its draft-spring, except as 55 controlled by the hand of the operator. I have shown the release-lever L as offset at l^4 , so that in the normal movement of the machine it may pass by the stop F without interfering with the same. The letter-space feed-rack is pivoted upon the paper-carriage B at R^5 , Fig. 4, just in the rear of the guide-rail C , where the usual pivot-rod r^6 and depression-spring r^7 are located.

The relative positions of the letter-space feed-rack pivot R^5 and the detent-finger r^3 are such that the lifting movement of the letter-space feed-rack under the influence of

the release-lever L causes the detent-finger r^3 to move toward the front of the machine in an arc of a circle. This movement advances 70 the end of the detent-finger so that it is arrested by the stop-finger f when the movement of the paper-carriage brings the detent-finger r^3 to the position occupied by the stop. When the releasing-lever L ceases to act upon 75 the letter-space feed-rack, which then falls to its normal position and meshes with its gear connections with the letter-space feed movements, the detent is retired out of its path of contact with the stop-finger f . 80

The stop F may be placed at will upon any part of the stop-rack d , or, if it is desired, two or more stops F may be employed and be located at desired intervals upon the stop-rack. This arrangement permits the type-writing 85 mechanism to perform all its normal functions without hindrance. Only when the operator desires to bring the paper-carriage to rest at a point determined by the location of the stop F upon the stop-rack can the stop 90 and detent coact with each other to arrest the carriage.

During all the normal letter-space and space-bar movements the detent-finger r^3 passes by the stop-finger f , and so, also, when 95 the carriage is returned to position for the beginning of a line these members of my tabulating attachment remain inactive.

By providing a stop or stops F , as shown and described above, the paper-carriage can 100 be arrested at a predetermined point or points, and accurate tabulation of a column or columns of figures may thus be facilitated. In order, however, to facilitate still further the accurate tabulation of columns of figures, I 105 have provided for an adjustable movement of the stop-rack d itself in the direction of its length. The knurled disk e , toothed wheel e' , and gear-wheel e^2 have been alluded to before. The teeth in the gear-wheel e^2 mesh with the lower tooth-space d^3 of the stop-rack d . A detent e^8 , pivoted at e^5 upon the plate E , is urged into contact with the gear-wheel e^2 by spring e^4 . 110

The toothed wheel e' is a mutilated gear having in this instance only four teeth. These teeth perform a double function. When the knurled disk e and toothed wheel e' are rotated together, one of the teeth of the wheel e' makes contact with and moves the detent e^8 out of contact with the teeth in the gear-wheel e^2 and holds it so removed while the next tooth in the wheel e' meshes with the gear-wheel e^2 and moves it the space of one tooth in the direction desired by the operator. This of course advances the stop-rack d in either direction by the space of one tooth, these tooth-spaces being equal to the letter-space of the type-writing machine. Thus the point of arrest of the paper-carriage 120 by a stop F may be changed at will without obliging the operator to shift the position of the stop upon the stop-rack. This mechanical feature performs its functions in connection with the letter-space feed-rack. 130

tion with the index scale and pointer, which appear upon the side of the tabulating attachment toward the operator of the machine.

An index-marker d^4 , Figs. 1 and 4, is secured to the stop-rack and points to an index-scale e^9 , which is marked upon the raised portion e^8 of the plate E. This index-scale, as shown in Figs. 1 and 4, represents the decimal-point and letter or figure spaces at either side, which correspond to tens, hundreds, thousands, &c., on one side of the decimal and decimal-fractions on the other side. Now supposing a column of figures representing sums of money is to be tabulated upon the paper in the machine and the operator finds that most of the figures are in thousands, a few in hundreds, and some in tens, with decimals representing cents, the operator places the stop F at a convenient point on the stop-rack and then by the aid of the disk e moves the stop-rack until the index-marker d^4 points to the fourth mark on the right of the decimal-point on the index-scale e^9 .

Movement of the carriage, upon release of the lever L will always be arrested by the stop F at the same point. In writing a sum having four figures before the decimal the operator begins immediately to write the figures after the stop F has arrested the carriage. When a figure in the hundreds is reached, the operator first strikes the space-bar and then writes the three figures before the decimal, and if the figure is in tens strikes the space-bar twice, and so on. When this column is inspected, it will be found that all the figures are accurately tabulated with the column of decimal-points in a true vertical line. No verification is required except as afforded by the index-marker d^4 and its position with relation to the index-scale e^9 .

If a column of figures contains, say, most of the sums in hundreds, with very few in the thousands, and the index is set for hundreds, the operator need not return the carriage after it is arrested by the stop and then verify the position of the carriage by raising it, but has only to advance the stop-rack one tooth before moving the paper-carriage to the stop. When the sum of larger denomination is put down, the stop-rack can then be returned to its convenient normal position for the column being written.

Tabulating attachments have been used for type-writing machines in which the carriage is released by pressing a special key, so that the carriage is moved quite violently into contact with the stop which forms part of the tabulating attachment. This mode of operation is quick, but results in unpleasant jar to the machine, and in order to prevent this condition of things I have provided the dash-pot stop above described, which may be used either with a tabulating attachment which embodies my invention or with other devices designed to accomplish a similar purpose.

What I claim, and desire to secure by Letters Patent, is—

1. In a tabulating attachment for type-writing machines of the traveling-paper-carriage class, the combination of a rack-frame adapted to attachment to the machine-frame, an adjustable stop-rack, mounted and movable upon the rack-frame, means secured to the rack-frame for adjusting and moving the stop-rack, a paper-carriage stop upon the stop-rack, and a detent carried by the paper-carriage and so placed as to make contact with the paper-carriage stop when the paper-carriage is lineally advanced by means other than its normal step-by-step feed mechanism.

2. In a tabulating attachment for type-writing machines of the traveling-paper-carriage class, the combination of a rack-frame adapted to attachment to the machine-frame, an adjustable stop-rack mounted and movable upon the rack-frame, a paper-carriage stop upon the stop-rack, a detent, carried by the paper-carriage and so placed as to make contact with the paper-carriage stop when the paper-carriage is lineally advanced by means other than its normal step-by-step feed mechanism, an index-marker carried by the stop-rack, and an index-scale adjacent to the stop-rack upon the stop-rack frame having a series of marks corresponding to the normal feed-spaces of the paper-carriage.

3. In a tabulating attachment for type-writing machines of the traveling-paper-carriage class, wherein the paper-carriage is advanced step by step by means, among other things, of a letter-space feed-rack, which is so mounted as to be susceptible of a movement of release out of mesh with the rest of the step-by-step feed mechanism, the combination of an adjustable stop-rack, a paper-carriage stop upon the stop-rack, and a detent, carried by the letter-space feed-rack, and so placed thereon as to make contact with the paper-carriage stop when the letter-space feed-rack is released from mesh with the feed mechanism and the paper-carriage is lineally advanced.

4. In a tabulating attachment for type-writing machines of the traveling-paper-carriage class, wherein the paper-carriage is advanced step by step by means, among other things, of a letter-space feed-rack, mounted so as to be susceptible of a movement of release out of mesh with the rest of the step-by-step feed mechanism, the combination of an adjustable stop-rack, a paper-carriage stop upon the stop-rack, a detent carried by the letter-space feed-rack, and so placed thereon as to lie out of reach of the paper-carriage stop while the letter-space feed-rack is in mesh with the step-by-step feed mechanism, and to move into contact reach of the paper-carriage stop when the letter-space feed-rack is moved out of mesh with the step-by-step feed mechanism.

5. In a tabulating attachment for type-writing machines of the traveling-paper-carriage class, the combination of a stop-rack, a paper-

carriage stop thereon, a detent carried by the paper-carriage, and so placed as to make contact with the paper-carriage stop when the paper-carriage is advanced independently of its normal step-by-step feed mechanism, and a dash-pot adapted to receive and absorb the shock of contact between the paper-carriage stop and the detent.

6. In a tabulating attachment for type-writing machines of the traveling-paper-carriage class, the combination of a stop-rack, a paper-carriage stop thereon, a detent carried by the paper-carriage and so placed as to make contact with the paper-carriage stop when the paper-carriage is advanced independently of its normal step-by-step feed mechanism, one of the two cooperating members (the paper-carriage stop and the detent) being mounted on the plunger of a dash-pot, whereby the shock of contact between the paper-carriage stop and the detent is absorbed.

7. In a tabulating attachment for type-writing machines of the traveling-paper-carriage class, the combination of a stop-rack, a paper-carriage stop thereon, a detent carried by the paper-carriage and so placed as to make contact with the paper-carriage stop when the paper-carriage is advanced independently of its normal step-by-step feed mechanism, a dash-pot adapted to receive and absorb the shock of contact between the paper-carriage stop and the detent, and automatic means for restoring the dash-pot to its receptive condition when contact between the paper-carriage stop and detent is broken.

8. In a tabulating attachment for type-writing machines of the traveling-paper-carriage class, the combination of a stop-rack, a paper-carriage stop thereon, a detent carried by the paper-carriage and so placed as to make contact with the paper-carriage stop when the paper-carriage is advanced independently of its normal step-by-step feed mechanism, one of the two cooperating members (the paper-carriage stop and the detent) being mounted on the plunger of a dash-pot, and a spring whereby the dash-pot plunger is restored to its normal position when the contact between the said members is broken.

9. In a tabulating attachment for type-writing machines of the traveling-paper-carriage class, the combination of a toothed stop-rack parallel with the line of feed of the paper-carriage, a guide therefor, means for adjustably moving the stop-rack in its guide, a pa-

per-carriage stop adapted to fit between the teeth of the stop-rack, a letter-space feed-rack, movable into and out of mesh with the letter-space feed mechanism, means for moving the letter-space feed-rack, a detent, secured to the letter-space feed-rack and so proportioned and placed as to make contact with the paper-carriage stop when the letter-space feed-rack is moved out of mesh with the letter-space feed mechanism, and to run clear of the paper-carriage stop when the letter-space feed-rack is in mesh with the letter-space feed mechanism.

10. In a tabulating attachment for type-writing machines of the traveling-paper-carriage class, the combination of a bed-plate, means for securing the bed-plate to the machine-frame, a guideway on the bed-plate, a toothed stop-rack movable in the guideway, means for intermittently sliding the stop-rack in its guideway, and a detent whereby the stop-rack is held in position between movements, a paper-carriage stop upon the stop-rack adapted to be secured in any tooth-space of the rack, and a detent, carried by the paper-carriage and so placed as to make contact with the paper-carriage stop when the paper-carriage is lineally advanced by means other than its normal step-by-step feed movement.

11. In a tabulating attachment for type-writing machines of the traveling-paper-carriage class, the combination of a bed-plate, means for attaching the bed-plate to the machine-frame, a guideway on the bed-plate, a toothed stop-rack movable in the guideway and parallel to the line of feed of the paper-carriage, a gear-wheel mounted on the bed-plate and in mesh with the stop-rack, a mutilated gear in mesh with the gear-wheel, a spring-pressed detent, engaging with the gear-wheel, and with the mutilated gear in such manner that when the mutilated gear is turned the detent is released thereby and held released while the gear-wheel and rack are moved, a paper-carriage stop on the stop-rack, and a detent carried by the paper-carriage, substantially as described.

Signed by me at Hamilton, Massachusetts, this 7th day of September, 1900.
